BOBBIN RECEPTACLE

Morris Schnider, Los Angeles, Calif.

Application October 10, 1938, Serial No. 234,269

6 Claims. (Cl. 242—137)

This invention relates to a bobbin receptacle and has as its primary object the provision of an improved container for sewing machine bobbins of the character used by operators of sewing machines in garment factories and in tailoring and dressmaking establishments.

Another object is to provide a bobbin holder of the above character which is adapted to contain a plurality of bobbins arranged in independent relation to each other and in such fashion as to permit the ready removal and replacement of a selected bobbin and in which the bobbins are so arranged as to expose the peripheral portions thereof on which the thread is wound thereby facilitating the selection by an operator of a bobbin containing a thread of desired color.

Another object is to provide a bobbin container embodying a rack which is so formed as to accommodate a plurality or series of bobbins loosely seated on portions of the perimeters thereof, in which means are provided for collectively clamping the bobbin against movement in the rack to prevent turning of the bobbin and consequent unwinding of thread therefrom on subjecting the container to vibrations and especially during transportation of the container.

A further object is to provide a bobbin container embodying a housing fitted with a hinged closure adapted to be fastened in a closed position to seal bobbins in the container, and in which means are provided in association with the cover for effecting a spring pressed clamping action on bobbins arranged edgewise in the container.

With the foregoing objects in view, together with such other objects and advantages as may subsequently appear, the invention is carried into effect as illustrated by way of example in the accompanying drawings, in which:

Fig. 1 is a perspective view of one form of the bobbin container with parts disposed in an open position;

Fig. 2 is a view in longitudinal section of the container shown in Fig. 1 with the parts disposed in a closed position and illustrating the manner of clamping a plurality of bobbins therein;

Fig. 3 is a detail in cross section taken on the line 3—3 of Fig. 2 as seen in the direction indicated by the arrows;

Fig. 4 is a detail in cross section taken on the line 4—4 of Fig. 2 as seen in the direction indicated by the arrows with the cover in an open position;

Fig. 5 is a detail in section taken on the line 5—5 of Fig. 2 as seen in the direction indicated by the arrows with the cover in an open position;

Fig. 6 is a perspective view of another form of the bobbin container with the parts disposed in a closed position and with portions broken away;

Fig. 7 is a plan view of the latch employed in the construction shown in Fig. 6 as seen in the direction of the arrow 7 of Fig. 6;

Fig. 8 is a view in cross section of the container shown in Fig. 7;

Fig. 9 is a detail in section taken on the line 9—9 of Fig. 6;

Fig. 10 is a view in longitudinal section of the container shown in Fig. 6; and

Fig. 11 is a perspective view illustrating the manner of mounting the bobbin container on a sewing machine and depicting the manner in which the structure shown in Figs. 6—10 inclusive may be removably housed within a container or housing affixed to the sewing machine.

Referring to the drawings more specifically, reference now being had to the construction shown in Figs. 1—5 inclusive, A indicates generally a box-like housing embodying a bottom wall 15, front and back walls 16 and 17 respectively, and end walls 18 and 19; the housing A also including a lid or cover 20 hinged at 21 to the upper margin of the back wall 17 to swing vertically and being adapted to be positioned with its outer margin overlying the front wall 16. The cover 20 is adapted to be locked in its closed position and for which purpose is here shown as fitted with a keeper 22 adapted to be engaged by a key controlled lock structure 23 on the front wall 16.

In carrying out the present invention the housing A is fitted interiorly thereof with a bobbin receiving rack B embodying a series of parallel channels 24 of arcuate cross section extending longitudinally of the bottom wall 15 of the housing.

Each of the channels 24 is adapted to receive a plurality of bobbins C; the bobbins being arranged on edge face to face in a row extending lengthwise of the channels which latter are formed to conform to the lower portion of the bobbins so as to hold the latter against rolling.

Pivoted supported within the housing A is a bobbin engaging leaf D adapted to engage the upper peripheral portions of the bobbins C to collectively hold the latter against displacement in the rack B when the cover 20 is closed; the leaf D being here shown as connected at one end thereof by pivot pins 25 to upturned ends 26 of a plate spring 27 carried by the end wall 18 which plate spring 27 affords a yieldable pivotal

support for the leaf D on which the latter may be swung vertically.

- Carried on the outer end of the leaf and projecting upwardly from the upper outer face thereof is a depressible button 28 having a reciprocal shank 29 against the inner end of which bears a spring 30 adapted to be compressed on depression of the button 28 which latter is adapted to be engaged and depressed by the cover 20 on moving 10 the latter to its closed positions. The under side of the leaf D is formed with channels 31 of arcuate cross section conformable to the upper portions of the bobbins and in which the latter seat when the leaf is in its closed position.
- 15 The bottom wall 15 of the housing A is fitted with openings 32 and 33 for the reception of screws or similar fastenings whereby the housing may be attached to a suitable support.
- In the operation of the form of the invention 20 just described a series of bobbins C are arranged in the rack B with the lower portions of the bobbins seating in the channels 24 and with the bobbins in each channel arranged side by side or end to end as illustrated in Fig. 2; the bobbins being 25 thus loosely supported in the rack in an upright position to facilitate selection of a particular bobbin and in a fashion permitting of their being separately and independently removed and replaced. When it is desired to close the bobbins 30 within the housing A the leaf D is swung on its pivot 25 to overlie the bobbins C as particularly shown in Fig. 2 with the channels 31 on the under side of the leaf receiving and conforming to the upper peripheral portions of the bobbins. On 35 closing the lid 20 and clasping it in a closed position the button 28 will be engaged and depressed in opposition to the spring 30 which with the spring mounting of the hinge pivots 25 will cause the leaf D to bear collectively on the series of 40 bobbins therebeneath under a yieldable pressure whereby the bobbins will be securely held in an upright position against displacement in the rack B either while carrying the housing A or under vibration thereof while fastened to a support, and 45 whereby on opening the lid 20 and lifting the leaf D the bobbins will be exposed in the position in which they were disposed on initially enclosing them in the housing. The spring-pressed member 28 is shown carried by the leaf D, but it could 50 be carried by the lid 20 without departing from the spirit of the claimed invention.
- In the form of the invention shown in Figs. 55 6-11 inclusive, E indicates a housing having a bottom wall 35, side walls 36 and 37 and end walls 38 and 39. A leaf 40 is arranged to overlie the housing E one end of which is fitted on its under side with a plate spring 41 having upturned end portions 42 engaged by pivot pins 43 on upstanding ears 44 formed on the end wall 38; the pins 43 60 and spring 41 forming a yieldable hinged mounting for the leaf 40 and on which the latter is hinged to swing vertically. The bottom wall 35 is formed with a series of parallel longitudinal extending channels 45 adapted to receive a series of 65 bobbins F arranged in an upright position and edge to edge as particularly shown in Fig. 10. The leaf 40 is formed with parallel channels 46 arranged to receive and engage the upper portions of the bobbins F seated in the channels 45.
- 70 Means are provided for clamping the leaf 40 against the bobbins F under spring pressure which is here shown as embodying a stem 47 mounted for longitudinal and turnable movement on the end wall 37; the stem 47 extending into a recess 49 in the end wall 37 and being fitted with 75

an end flange 49 between which and a shoulder 50 is arranged an expansion spring 51 which exerts an inward thrust on the stem 47. An elongated head 52 on the upper outer end of the stem 47 is movable in and out of engagement with the free end of the leaf 40 and is adapted when engaged with the leaf, as shown in Fig. 10, to impose inward pressure on the latter under the urge of the spring 51 and thus cooperate with the spring 41 to clamp the bobbins F against displacement in the channel 45 during transportation of the housing.

The housing E is adapted to be positioned within a housing G similar to the housing A previously described, which housing G may be 15 attached to the shelf H of a sewing machine, as shown in Fig. 11. The housing G is provided with a cover 53 adapted to be fastened in a closed position by a key controlled lock 54. The mode of 20 operation of the form of the invention just described is apparent from the foregoing.

An important feature of the invention resides in the fact that by arranging and holding the bobbins on edge in the container they are not only 25 subject to being easily and quickly selected and removed and replaced, but when clamped in the container are held against turning so as to prevent unwinding of thread therefrom, thereby effecting a great saving in thread since it is customary for an operator to break off and discard 30 any unwound length of thread on a bobbin he is about to place in a machine. The invention thus enables economy in thread and a saving in labor as well as affording a convenient means of conveying and housing the bobbins when not in use. 35

While I have shown and described specific embodiments of my invention I do not limit myself to the exact details of construction set forth, and the invention embraces such changes, modifications and equivalents of the parts and their 40 arrangement and arrangement as come within the purview of the appended claims.

I claim:

1. In a bobbin receptacle, a housing, means in 45 said housing for supporting a plurality of bobbins in an upright position, a leaf pivotally carried by said housing, bobbin engaging means on said leaf, and a lid hinged to said housing for clamping said leaf against bobbins contained in said housing, there being a spring-pressed member positioned 50 between said leaf and lid to impart a yielding pressure to said leaf.

2. In a bobbin receptacle, a housing, means in 55 said housing for supporting a plurality of bobbins in an upright position, a leaf pivotally carried by said housing, bobbin engaging means on said leaf and a hinged lid on said housing adapted to overlie said leaf and arranged to clamp said leaf against bobbins contained in said housing when 60 in its closed position.

3. In a bobbin receptacle, a housing having a bottom wall fitted with a series of bobbin receiving channels formed to support bobbins on edge therein, a leaf adapted to be positioned to extend over bobbins in said channels having channels on 65 its under side arranged to receive the upper portions of bobbins in said first named channels, and a lid hinged to said housing for holding said leaf against bobbins in said channels, said leaf carrying an upwardly directed spring-pressed part engageable by said lid to cause said leaf to impose a yielding pressure on the bobbins when said lid is closed.

4. In a bobbin receptacle, a housing having a bottom wall fitted with a series of bobbin receiv- 75

- ing channels formed to support bobbins on edge therein, a leaf adapted to be positioned to extend over bobbins in said channels having channels on its under side arranged to receive the upper portions of bobbins in said first named channels, and a lid hinged to said housing for holding said leaf against bobbins in said channels, said leaf carrying a spring and a button pressed upwardly thereby and engageable by said lid for imposing spring pressure on the bobbins.
5. In a bobbin receptacle, a housing, a bobbin supporting rack in said housing adapted to support bobbins on edge, a leaf adapted to extend over and to seat on bobbins in said rack, resilient hinge connections between said leaf and said
- 10
- 15

housing, and a lid hinged to said housing for clamping said leaf against bobbins in said rack to hold the bobbins against displacement, there being a spring member positioned between the free end portion of said leaf and the overlying portion of said lid when the latter is closed to cause a yielding pressure of said leaf upon the bobbins when said leaf and lid are in their closed positions.

6. The subject matter of claim 5 and, said spring member consisting of a spring carried by said leaf and a button pressed upwardly by said spring.

MORRIS SCHNIDER. 15
